UNITED STATES PATENT OFFICE

RICHARD KIMBERLEY SPENCER, OF ROTHBURY, WALLINGTON, ENGLAND, ASSIGNOR
TO RADIO CORPORATION OF AMERICA, A CORPORATION OF DELAWARE

WIRELESS RECEIVER

Application filed January 21, 1924, Serial No. 687,403, and in Great Britain January 25, 1923.

This invention relates to valve receivers and its object is to provide means whereby a receiving set designed to work without reaction may have reaction applied to it without any alteration to the permanent connections of the set.

According to this invention I provide a block in which the reaction device is mounted and which has on its plugs adapted to fit into the valve sockets of the set and has in it sockets adapted to receive the valve pins. Thus, when it is desired to employ reaction, all that need be done is to remove the valve from its socket in the receiving set, insert the block in that socket and insert the valve in the socket in the block.

The invention is illustrated by way of example in the accompanying drawings.

Figure 1 of which is a plan of the block and

Figure 2 a section.

Figure 3 is a diagram of the connections of the block and

Figure 4 is a diagram of the circuit when the device is in use and arranged for producing regeneration.

Referring to the drawings a block 1 composed of insulating material has in it plugs or pins D E F adapted to make contact with three of the contacts of the socket of a three electrode valve of the receiving set. These three contacts of the socket normally, that is when the block is not in use, receive or make electrical connection with the pins of the valve which are connected to the grid, one end of the filament, and the anode respectively. The pin D is permanently connected by a conductor 2 to a socket A as indicated in Fig. 3; and the pin E is permanently connected to a socket B by conductor 3.

When the block is in use, the anode pin of the valve fits into the socket C, one of the filament pins into the socket B and the grid pin into a third socket A, while the other filament pin passes through a hole K in the block into contact with contact X of the socket of the valve of the receiving set with which the other filament pin of the valve contacts when the block is not in use.

The block also has formed in it three

sockets G H J into which can be inserted plugs g h j represented diagrammatically in Figure 1 and connected to a condenser L and an inductance M as shown diagrammatically. The socket J is permanently connected to the pin F by conductor 4. N is a condenser permanently secured in the underside of the block and connected by conductors 5 and 6 between the sockets J and H, the latter of which is connected to the socket C by conductor 7. Socket A is connected to socket G by conductor 8.

It will be understood that when it is desired to introduce reaction or regeneration, the valve is lifted out of the sockets of the receiving set, the block is placed in position with the pins D E and F fitting into the three said sockets and the valve pins are then inserted into the sockets A B C and through the hole K into one of the sockets in the valve set, whereupon a reaction unit fitted with plugs g h j and comprising a condenser L and inductance M is fitted on top of the block.

For a better understanding of the invention I have shown in Fig. 4 a diagram in which the circuit connections within the dotted rectangle corresponds with the circuit of a standard non-regenerative receiver having a tuned antenna circuit coupled to a tuned grid circuit and having the grid leak connected from the filament to the grid and a grid condenser between the tuned input circuit and the grid. A filament and a plate battery and an indicator are also shown in a conventional manner. The connections outside of the rectangle are those supplied by the adapter block when the three element valve is fitted in the block sockets. From this diagram it would be seen that the condenser N and inductance M are connected in the plate circuit and are adapted to permit the latter to be tuned whereby coupling is achieved through the capacity of the tube in the well-known manner. The condenser L connected from the grid to the plate increases the effective capacity of the tube and assists in the production of feedback or regeneration.

While I have shown a particular manner of applying my invention by utilizing a particular kind of regenerative circuit it may be

readily embodied in other forms and I do not therefore wish to be understood as limiting the invention to the form herein shown but seek to claim my invention in any form in which it may be embodied. The scope of my invention is to be determined by reference to the accompanying description and particularly to the claims attached thereto.

Having described my invention what I claim is:—

1. An attachment for obtaining regeneration adapted to be inserted into a socket ordinarily used with a three electrode vacuum tube, comprising a block, means in said block for receiving the electrode terminals of the vacuum tube, and additional means in said block for receiving plate tuning means.
2. An attachment for obtaining regeneration adapted to be inserted into a socket ordinarily used with a three electrode vacuum tube, comprising a block, means in said block for receiving the electrode terminals of the vacuum tube, and a reaction device mounted within said block.
3. In a non-regenerative circuit arrangement including a three electrode vacuum valve and associated socket, means for changing said circuit arrangement to one of regeneration, comprising a block adapted to be inserted in said socket, terminals in said block for receiving the electrode terminals of said vacuum tube, and additional terminals for receiving plate tuning means.
4. In high frequency signalling systems, the combination with a socket for a three electrode valve adapted to be connected to a suitable receiving circuit, of a device for changing the receiving circuit, said device having contacts adapted to cooperate with said socket and having a socket for receiving the terminals of the valve, connections from certain of said contacts to certain of the terminals of the last mentioned socket and means for connecting a tuning element between another of the contacts and another of the terminals of said last mentioned socket.
5. In high frequency signalling systems, the combination with a socket for a three electrode valve adapted to be connected to a suitable receiving circuit, of a device for changing the receiving circuit, said device having contacts adapted to cooperate with said socket and having a socket for receiving the terminals of the valve, connections from certain of said contacts to certain of the terminals of the last mentioned socket and a pair of terminals connected between another of the contacts and another of the terminals of the last mentioned socket.
6. In a high frequency signalling system, the combination with a socket for a three electrode valve adapted to be connected to a suitable receiving circuit, said socket having contacts for the terminals adapted to

cooperate with the grid plate and filament terminals of the valve, a device for changing the receiving circuit having contacts cooperating with said socket to connect with the grid, plate and filament contacts of the first mentioned socket and having a socket with contacts for cooperating with the grid, plate and filament terminals of the valve, the grid contacts of said device being connected together and said filament contacts of said device being also connected together, a pair of terminals, a connection from one of said terminals to the plate contact of the socket of the device and a connection from the other terminal to the contact which is adapted to engage this plate contact of the first mentioned socket.

7. A device for converting a non-regenerative circuit to a regenerative circuit comprising a block having contacts adapted to be received by a three electrode valve socket, a socket in the device for receiving a three electrode valve, terminals for receiving a tuning element, connections from certain of the first mentioned contacts to certain of the contacts of the last mentioned socket, a connection from another of the first mentioned contacts to one of the terminals and a second connection from another of the contacts of said last mentioned socket to the other terminal.

8. A device for converting a non-regenerative circuit to a regenerative circuit including three pins adapted to contact with three of the four contact members of a three electrode valve socket, means providing three orifices to receive three of the prongs of said valve, and means providing an aperture to receive the fourth prong of said valve, whereby the fourth prong is adapted to contact the fourth contact member of the socket.
